UNITED STATES PATENT OFFICE.

AXEL WELIN, OF LONDON, ENGLAND.

APPARATUS FOR RAISING OR LOWERING SHIPS' BOATS &c.

SPECIFICATION forming part of Letters Patent No. 680,828, dated August 20, 1901.

Application filed May 27, 1901. Serial No. 62,103. (No model.)

To all whom it may concern:

Be it known that I, AXEL WELIN, engineer, a subject of the King of Sweden and Norway, residing at 24 and 25 Fenchurch street, in the 5 city of London, England, have invented certain new and useful Improvements in Apparatus for Raising or Lowering Ships' Boats, of which the following is a specification.

According to this invention the davit turns 10 about a center moving along guides, and its lower end is in the form of a toothed quadrant, preferably circular, rolling on a rack. The weight of the boat and its contents tend to make the quadrants roll on the racks, inclining the davits more and more and at the 15 same time moving them outward. Each davit carries a pawl engaging with a rack in order to prevent the davits from being brought back by the rolling of the ship, or the motion of the davit may be controlled by 20 a screw or other means. If the davits are curved and inboard of the boat, they need not be at the ends of the boat.

Figures 1 and 2 are side elevations of davits 25 constructed according to this invention. Fig. 3 is an elevation, and Fig. 4 a plan, of the chocks employed.

a is the davit, carrying a pin *b*, running between guides *c*.
30 In Fig. 1 the pin *b* works in a block *d*, sliding between the guides, while in Fig. 2 the pin *b* is in the form of a roller running between the guides.

e is a toothed quadrant forming the lower 35 part of the davit, and *f* is a rack on which it rolls.

In Fig. 1 the motion is controlled by the screw *g*, working in a nut formed in a lug on the block *d*, while in Fig. 2 the outward motion is controlled by the rope *h*, and the davit 40 is prevented from being swung back by the rolling of the ship by the pawl *k*, which gears with the rack *l*.

The chock *m* is fixed and supports one end 45 of the chock *n*, whose other end is supported by the link *o*. The chock *n* is secured in position by the lever-catch *p*. To lower the boat, the lever-catch *p* is raised out of the hook *q*, and then as the boat moves outward 50 it pushes the chock *n* with it into the position shown in dotted lines in Fig. 3.

In cases where the apparatus may be in danger of getting covered by ice a hole is bored lengthwise through the body of the 55 rack and connected with a steam-pipe. By

this means the ice is melted and the gear kept in working order.

What I claim is—

1. The combination of a davit, a pivot about which the davit can turn, guides for the pivot, 60 a toothed segment at the lower end of the davit, and a rack on which the segment can roll.

2. The combination of a davit, a pivot about which the davit can turn, guides for the pivot, 65 means for controlling the movement of the pivot in the guides, a toothed segment at the lower end of the davit, and a rack on which the segment can roll.

3. The combination of a davit, a pivot about 70 which the davit can turn, a block carrying the pivot, guides for the block, a nut fixed to the block, a screw working in the nut, a toothed segment at the lower end of the davit, and a rack on which the segment can 75 roll.

4. The combination of a davit, means for moving the top of the davit outward, a stationary chock, a second chock supported at one end by the first, and links supporting the 80 other end of the second chock.

5. The combination of a davit, a pivot about which the davit can turn, guides for the pivot, a toothed segment at the lower end of the davit, a rack on which the segment can roll, 85 a stationary chock, a second chock supported at one end by the first, and links supporting the other end of the second chock.

6. The combination of a davit, a pivot about which the davit can turn, guides for the pivot, 90 means for controlling the movement of the pivot in the guides, a toothed segment at the lower end of the davit, a rack on which the segment can roll, a stationary chock, a second chock supported at one end by the first, and 95 links supporting the other end of the second chock.

7. The combination of a davit, a pivot about which the davit can turn, a block carrying 100 the pivot, guides for the block, a nut fixed to the block, a screw working in the nut, a toothed segment at the lower end of the davit, a rack on which the segment can roll, a stationary chock, a second chock supported at one end by the first, and links supporting 105 the other end of the second chock.

AXEL WELIN.
